UNITED STATES PATENT OFFICE.

JOHN ELDRIDGE, OF OAKLAND, CALIFORNIA, ASSIGNOR TO ROBERT S. DOLLAR, OF OAKLAND, CALIFORNIA.

BRICK-VENEERING MACHINE.

1,315,916.

Specification of Letters Patent. Patented Sept. 9, 1919.

Application filed July 27, 1917. Serial No. 183,070.

To all whom it may concern:

Be it known that I, JOHN ELDRIDGE, citizen of the United States, residing at Oakland, in the county of Alameda and State 5 of California, have invented certain new and useful Improvements in Brick-Veneering Machines, of which the following is a specification.

This invention is an improved brick veneering machine for glazing, enameling, or surface coating bricks with plastic material.

One of the objects of the invention is to provide a machine capable of rapidly applying the desired coating. A further object is to provide means for doing this uniformly, delivering the bricks evenly coated with clean, sharp edges on the veneer.

The invention will be hereinafter fully set forth, and particularly pointed out in 20 the claims.

In the accompanying drawings:

Figure 1 is a vertical side view of my improved brick veneering machine. Fig. 2 is a view similar to Fig. 1 with the framework removed, parts of the machine being in section and parts being broken away. Fig. 3 is a front end elevation. Fig. 4 is a vertical section on the lines 4—4 of Fig. 2. Fig. 5 is a rear end elevation. Fig. 6 is a 30 section of a reservoir showing an actuator and means for operating same. Fig. 7 is a section showing a modified form of the lower portion of reservoir shown in Fig. 6. Fig. 8 is a sectional view of a feed mechanism. Fig. 9 is a detail of a link carriage. Fig. 10 is an end view of same. Fig. 11 is a reverse end view of Fig. 10. Fig. 12 is a section of same on line 12—12 of Fig. 11. Fig. 13 is a perspective front view of a 40 carriage casting. Fig. 14 is a rear perspective view of same. Fig. 15 is a perspective view of an edger plate.

Referring to the drawings, the four vertical corner posts of a framework, composed of channel iron, are designated at 1. Bolted to the tops of said corner posts and connecting same are two side braces 2, also of channel iron, and at a distance slightly above the center of the corner posts 1, are 45 secured on either side of the framework longitudinally extending channel irons 3. The said side channels 3 serve as additional braces to the framework and also act as a carriage for various working parts herein- 50 after described. The said side channels ex-

tend a considerable distance beyond the length of the top side braces 2, to form supports or carriages respectively for feed and delivery into and from the machine. The channels 3 are braced to the corner 60 posts 1 by oblique braces 4. The two sides of the frames are joined by a yoke 6 at one end and by a yoke 7 at the opposite end.

At a point near the middle of the length of the channel irons 3, and secured to the upper edges thereof, are bearings 8, in which rotates a shaft 9, driven by a pulley 11, belted or otherwise connected to any suitable source of power. Keyed to said shaft, as shown at 12, is a pinion 13, meshing with 70 and imparting motion to a gear 14, keyed to a shaft 16, as shown at 17. Extending outwardly from the said gear 14, is a stud shaft 18, on which is pivoted one end of a connecting rod 19, the other end of which 75 is pivotally connected to one end of a rocker arm 21, pivoted near its center on a shaft 22, rotatably mounted in bearings 23, secured to the upper edge of channels 3. Keyed to the shaft 22 as shown at 24 is a 80 ratchet wheel 26, having teeth actuated by a pivoted pawl 27, carried by the upper end of the rocker arm 21, six teeth being shown. Also keyed to said shaft 22 is a pair of sprocket wheels 28. The purpose of this 85 construction is to impart an intermittent motion to the sprockets 28, from the continuous rotation of the shaft 13. It will be readily understood that as the pinion 13 rotates the gear 14, the stud shaft 18 actuates the connecting rod 19, thereby reciprocating the rocker arm, once for each revolution of the gear 14. By the engagement of the pawl 27 with one of the six teeth of the ratchet wheel 26, the shaft 22 is rotated one- 90 sixth of a revolution while the shaft 16 rotates a half revolution, and that the said shaft 22 rests during the other half of each revolution of the shaft 16, while the rocker arm 21 returns the pawl 27 for reengagement.

The sprockets 28 drive an endless chain of link and pin construction hereinafter described, which also surrounds sprocket wheels 29 of the same diameter and construction as the sprocket wheels 28. The said sprocket wheels 29 are keyed to a shaft 31 rotatable in bearings 32 secured to the upper surface of the channels 3.

Keyed to the shaft 16 is a crank disk 33, 110

- on which is a stud shaft 34, to which is pivoted one end of a connecting rod 36, the opposite end of which is slidably connected to one end of a rocker arm 37, secured at its center on a shaft 38, rotatable in bearings 39, bolted to the lower surfaces of the channels 3.
- On the shaft 38 near its middle, is keyed one end of a lever arm 41, the opposite end 10 of which is bifurcated to admit one end of a link 42 pivoted thereto. The opposite end of said link 42 is pivotally connected, as shown at 43, to a downwardly projecting tongue 44 of a slide piece 46, slidable on the 15 nether surface of the yoke 6. Through a slot 45 in the upper wall of said yoke 6, extend bolts 47 which connect slide piece 46 with a pusher plate 48, having a downwardly extending tongue slidable in the 20 slot 45.
- The aforementioned slidable connection between the connecting rod 36 and one end of rocker arm 37 is made as follows: The connecting rod 36 extends through a hole in 25 a wrist pin 49 pivoted to one end of rocker arm 37. On said extension of the connecting rod 36, is a coiled tension spring 51, one end of which bears against the wrist pin 49 and the other against a washer 52, slidable on 30 said extension and held in position thereon by lock nuts 53. The purpose of this construction is to obviate any difficulty arising from an interruption or clogging of bricks in the feeding mechanism. It will be seen 35 that when the connecting rod 36 is reciprocated by the crank disk 33, the pusher plate 48 is alternately advanced and withdrawn on the surface of the yoke 6. Should the said pusher plate 48 encounter an obstruction in its advance the strain would be applied to the relief spring 51, which compresses and allows the extending portion of 40 the connecting rod to slide in the hole in the wrist pin 49.
- Bolted to the upper surface of the yoke 6 are vertical guide plates 54, of substantially 45 channel iron construction, having inwardly extending vertical members 56, adapted to keep a number of bricks in vertical alignment for feeding into the chain conveyer. The said vertical walls 56 are cut away at 50 their lower ends, as shown at 57, at a height sufficient to allow the free passage of a bottom brick of a series of bricks piled thereon.
- It will be seen that every revolution of 55 the shaft 16 causes one brick to enter the conveyer and obviously it is necessary to remove one from said conveyer at the same time.
- In order to accomplish this the lower end 60 of rocker arm 37 is provided with a wrist pin 58 pivoted thereon. To the said wrist pin is secured one end of a connection rod 59, on the other end of which is a wrist pin 60, pivoted on one end of a lever arm 61, the 65 other end of which is keyed to a shaft 62, rotatable in bearings 63, bolted to the lower edges of channels 3. Rocker arms 64 are keyed at one end to shaft 62, the other ends of said arms being provided with slots 66, 70 in which are bolted thin strips of steel having rounded ends, as shown at 67. As the shaft 62 is rotated, the rocker arms 64 bring the steel strips 67 into contact with one surface of a brick, and slide said brick out of 75 the chain conveyer onto the upper edges of parallel bars 68 bolted to the yoke 7.
- On the outer surfaces of the channels 3 are bolted bearings 69, in which rotates a shaft 71, to which are keyed grooved pulleys 72 80 around which pass continuous cables 73 and 74. The purpose of the pulleys and cables is to provide a means of transporting the veneered bricks as they leave the chain conveyer to a remote place for drying or stor- 85 age.
- Each unit of the chain conveyer consists of two parallel links 76 (Fig. 9), having holes in either end to receive pins 77. Within each of said units and extending vertically between the links 76 is a carriage casting 78. Each carriage casting has a vertical member 79, extending below the level of the links 76, two horizontal bracket members 81, having their outer faces grooved as 90 indicated at 82, for engagement with the links 76, a shelf member 83, integral with said brackets and having mortises 84, a vertical wall member 86 having oblique slots 87 therein, and a horizontal top member 88, on 100 a plane parallel to that of the shelf 83. The vertical member 79 is of L-shaped construction and with the brackets 81, forms a bearing for a slide bar 89, slidable vertically in said bearing when actuated by a roller 91 105 mounted on a stud shaft 92, secured to said slide bar 89. The said slide bar 89 is held in place by a face plate 93 secured by bolts 94 to the edge of the vertical member 79. The purpose of this construction of the carriage 110 castings is to provide a means of grasping, conveying, and delivering the bricks throughout the various portions of the machine. The units are arranged in pairs as shown in Fig. 9, the bricks being carried 115 between the opposed faces of the vertical walls 86 and resting upon the shelf members 83.
- In order to compensate for any inequality of the thickness of the bricks it is necessary 120 that one member of the carriage be flexible. This is accomplished in the following manner:—One member of each pair of carriage units (see Fig. 9), is fixedly secured to the links 76 by a bolt as shown at 96 while 125 the other member of each pair is slidable between the contiguous links 76, and pressed against the opposed fixed member by a

coiled spring 97, bearing at one end against the bottom of a hole in a boss 98, integral with the face plate 93, and bearing at the opposite end in a boss 99 integral with a sleeve 101 surrounding the contiguous pin 77. Mounted on the shaft 31 is a yoke 102, and similarly mounted on shaft 22, is a yoke 103. The yokes 102 and 103 are connected by longitudinal bars 104 and 105 which prevent 10 said yokes from being rotated by the shafts 31 and 22, which rotate therein. In the yokes 103 is a cam groove 100, a portion of which is coaxial with shaft 22. The purpose of said cam groove is to engage and depress 15 the rollers 91 as they enter said cam groove at 106, holding said rollers in depression while they traverse that portion of the cam groove that is coaxial with the shaft 22, and return said rollers 91 to their normal 20 position as they leave the cam groove 100.

Keyed to the shaft 16 (see Fig. 2) is a cam disk 107, having a cam groove 108 in its face to engage a roller 109, revoluble on a stud shaft 111, secured to one end of a rocker arm 25 112, the other end of which is secured to a shaft 113. The cam groove 108 has two segments that are coaxial with the shaft 16, allowing the rocker arm 112 to rest while the roller 109 traverses said segments and reciprocate the shaft 113 while traversing the 30 remaining portions of said cam groove. Two rocker arms 114 are secured at one end to the shaft 113 the other ends of said arms being pivoted to the ends of connecting rods 116, 35 pivotally connected to a sliding yoke 117, slidable in a yoke 118 bolted to the channel irons 2. Suitably secured to the inner walls of the yoke 117 is a U-shaped knife 121. Said knife 121 has two functions, *i. e.* it is 40 adapted to enter and close a rectangular opening 122 in the base of a reservoir 123, containing plastic material for the veneer to be applied to bricks, and is intended to be withdrawn from said opening when a brick 45 has been placed therein by the chain conveyor, allowing the plastic material to gravitate over the edges of said brick and then enter and close said reservoir as the brick is removed from the opening 122. It will be 50 seen that the cam disk 107, times these operations to the intermittent movement or steps of the chain conveyor.

The reservoir 123 is bolted to channel irons 2 and is wedge shaped at its base forming a hopper for delivering into opening 122, and is cylindrical in form above to permit the rotation agitators 124, of propeller construction secured to a vertical shaft 126, rotating in vertical bearings 127, of a casting 128, bolted to the flange 129 of said reservoir. The agitators are driven by a bevel gear 131 keyed to shaft 126. The gear 131 meshes with a like bevel gear 132, keyed to a shaft 133, rotating in a horizontal bearing 65 134, in the casting 128. Keyed to shaft 133,

is a sprocket wheel 136, driven by an endless chain 137 actuated by a sprocket wheel 138, keyed to shaft 13.

In operation, the machine is started by applying power to pulley 11, which through gear 33 the connecting rod 36 and slide 46, causes the lower brick of a pile in the feed guide 56, to be drawn into the chain conveyer. The chain is advanced step by step, until the brick arrives at the openings 122, in reservoir 123, where it remains during the period between the steps of movement of the chain. While the chain is stopped the U-shaped knife 117 is withdrawn, the brick coated, and the knife 117 then returned to close the 80 hopper of the reservoir, whereupon the chain undergoes the next step of its movement. As the coated brick nears the delivery end of the machine, the roller 91 is depressed by cam groove 100 drawing the slide 85 bar 89 downward. The slide bar 89 is pivotally connected with the inner ends of links 141, the outer ends of which are pivoted to bolts 142, extending through holes 143 in edger plates 144. The edger plates are provided with oblique guides 146, slidable in oblique slots 147, in the vertical wall 79 of casting 78. As the roller 91 depresses the slide bar 89, the edger plates are drawn obliquely downward by wiping the edges of 95 the veneered brick at the corners, leaving square edges on the ends and corners of same as it is delivered on the cables 73.

During the process so far described, the brick has occupied the position in the carriage shown in Fig. 13, in dotted lines. It will be seen that the downward oblique movement of edger plates 144 has edged the ends and a portion of the top of the brick. In order to edge that remaining portion of the top between the points 148 and 149, I have provided a means of raising the brick in the carriage to produce a vertical wiping stroke. Suitably secured to the inner sides of the channels 2, as shown at 151 are guide strips, 110 intended to raise the coated bricks as they encounter and are pushed over inclined portions 152 of said guides, changing the position of the brick in relation to the carriage, which wipes the remaining portions of the 115 top after the edger plates have finished the sides and corners.

It will be seen that it is necessary to provide a means of closing the reservoir 123 while the machine is running and any cessation or interruption in the feed occurs. In order to do this, I have made a U-shaped knife 153 which telescopes over the U-shaped knife 117. The knife 153 is connected to a sliding yoke 154, slidable in a yoke 156, 120 bolted to the channels 2. To a stud shaft 157, in said yoke 156, is pivoted one end of a link 158, the opposite end of which is pivoted to a rocker arm 159, secured to a shaft 161. The shaft 161 is rotated by a lever 162 keyed 130

thereto. The said lever 162 is provided with a latch 163 for engaging notches in a segment rack 164 bolted at its ends to a channel 2 and the reservoir 123.

5. It is sometimes desirable to veneer one side or end, or one side and one end only, of a brick. In order to do this, I have provided lining plates 166 securable within the sides of the opening 122, (see Fig. 7), by screws 167. It will be seen that the said lining plates 166 occupy the space of the veneer to be left off and do not in any way interfere with the action of the telescoping U-knives 117 and 153.
15. Having thus explained the nature of the invention, and described an operative manner of constructing and using the same, although without attempting to set forth all of the forms in which it may be made, or all 20 of the forms of its use, the following is claimed:
1. An improved brick veneering machine comprising a supporting frame, a conveyer for the bricks, means for actuating the conveyer, means for applying plastic material to the bricks while supported by the conveyer, and means carried by the conveyer for squaring-off the applied plastic material.
2. An improved brick veneering machine comprising a supporting frame, a conveyer provided with sectional brick receiving carriers, means for actuating the conveyer, means for applying plastic material to the bricks while supported by the respective carriers, and means connected with each carrier for squaring-off the applied plastic material.
3. An improved brick veneering machine comprising a supporting frame, a conveyer for the bricks, means for actuating the conveyer, means for applying plastic material to the bricks while supported by the conveyer, means carried by the conveyer for squaring-off the applied plastic material, and means for successively operating the squaring-off means during the travel of the conveyer.
4. An improved brick veneering machine comprising a supporting frame, a conveyer provided with sectional brick-receiving carriers, means for actuating the conveyer, means for applying plastic material to the bricks while supported by the respective carriers, means connected with each carrier for squaring-off the applied plastic material, and means for actuating the squaring-off means of each carrier when the latter reaches a predetermined point in the travel of the conveyer.
5. An improved brick veneering machine comprising a supporting frame, a conveyer provided with sectional brick-receiving carriers, means for actuating the conveyer, means for applying plastic material to the

bricks while supported by the respective carriers, edger plates supported by the said carriers, and means for periodically actuating said edger plates.

6. An improvement in brick veneering machines comprising a frame, a plurality of pivotally connected conveyer links, complementary carriage units attached to said links, plastic-applying means, and means for causing said carriage units to travel past said plastic-applying means.

7. An improvement in brick veneering machines comprising a frame, a plurality of pivotally connected conveyer links, complementary carriage units each having a bracket 80 member attached to contiguous links and a superposed shelf member, plastic-applying means, and means for causing said carriage units to travel past said plastic-applying means.

8. An improvement in brick veneering machines comprising a frame, a plurality of pivotally connected conveyer links, complementary carriage units attached to said links, plastic-applying means, means for causing 90 said carriage units to travel past said plastic-applying means, and edge-squaring devices carried by the carriage units.

9. An improvement in brick veneering machines comprising a frame, a plurality of 95 pivotally connected conveyer links, complementary carriage units attached to said links, side bars carried by said carriage units, edge squaring members actuated by said slide bars, plastic-applying means, means 100 for causing said carriage units to travel past said plastic-applying means, and means for operating said slide bars.

10. An improvement in brick veneering machines comprising a frame, a plurality of 105 pivotally connected conveyer links, complementary carriage units attached to said links, edger-plates carried and guided by said carriage units, means for operating said edger plates, plastic-applying means, 110 and means for causing said carriage units to travel past said plastic-applying means.

11. An improvement in brick veneering machines comprising a frame, a plurality of pivotally connected conveyer links, complementary carriage units attached to the links and provided with inclined guideways, edger plates mounted in said guide ways, means for operating said edger plates, plastic-applying means, and means for causing 120 said carriage units to travel past said plastic-applying means.

12. An improvement in brick veneering machines comprising a frame, a plurality of pivotally connected conveyer links, complementary carriage units attached to the links and provided with inclined guideways, edger plates mounted in said guideways, slide bars movably supported by said carriage units, connections between said slide 130

bars and the contiguous edger-plates, plastic-applying means, means for causing said carriage units to travel past said plastic-applying means, and means for actuating said 5 slide bars.

13. An improvement in brick veneering machines comprising a frame, a plurality of pivotally connected conveyer links, complementary carriage units attached to said links, 10 and provided with brick-engaging walls, edge and end squaring means carried by said walls, plastic-applying means, means for causing said carriage units to travel past said plastic-applying means, and means for 15 moving the bricks relatively to said walls to square the tops of the applied plastic surfaces.

14. An improvement in brick veneering machines comprising a frame, a plurality of 20 pivotally connected conveyer links, complementary carriage units attached to said links, plastic-applying means, means for causing said carriage units to travel past said plastic-applying means, and means for 25 moving the bricks relatively to the carriage units to square the tops of the applied plastic surfaces.

15. An improvement in brick veneering machines comprising a frame, a plurality of 30 pivotally connected conveyer links, complementary carriage units attached to said links, plastic-applying means, means for causing said carriage units to travel past said plastic-applying means, and guide strips positioned to engage the bricks and shaped to move them relatively to the carriage units 35 to square the tops of the applied plastic surfaces.

16. An improvement in brick veneering 40 machines comprising a frame, a brick-engaging conveyer, means for applying plastic to bricks carried by said conveyer, end and edge squaring devices carried by the conveyer, means for successively operating said 45 devices, and means for effecting relative movement between the coated bricks and the conveyer to square the tops of the coated surfaces.

17. An improvement in brick veneering 50 machines comprising a frame, a plurality of pivotally connected conveyer links, complementary carriage units attached to said links, said units having means for compensating for inequalities in the thickness of the bricks, 55 plastic-applying means, and means for causing said carriage units to travel past said plastic-applying means.

18. An improvement in brick veneering machines comprising a frame, a plurality of 60 pivotally connected conveyer links, pairs of complementary carriage units carried by said links, the units of each pair being slidably mounted with respect to each other, yieldable means for holding the units of the respective pairs together, plastic-applying

means, and means for causing said carriage units to travel past said plastic-applying means.

19. An improvement in brick veneering machines comprising a frame, a plurality of 70 pivotally connected conveyer links, pairs of complementary carriage units carried by said links, one unit of each pair being fixedly secured to the contiguous links the other unit being slidably supported by its links, means 75 for yieldably holding the units of the respective pairs together, plastic-applying means, and means for causing said carriage units to travel past said plastic-applying means. 80

20. An improvement in brick veneering machines comprising a frame, a plurality of pivotally connected conveyer links, pairs of complementary carriage units carried by said links, one unit of each pair being fixedly 85 secured to the contiguous links, the other unit being slidably supported by its links, springs interposed between the slideable units and the next adjacent links, plastic-applying means, and means causing said carriage 90 units to travel past said plastic-applying means.

21. An improved brick veneering machine comprising a frame, a traveling conveyer for supporting the bricks, means for imparting a step by step movement to said conveyer, a reciprocable feed slide operated in time with the movements of said conveyer, means for supplying bricks to said slide, and means for applying coating material to the 100 bricks while supported by said conveyer. 95

22. An improved brick veneering machine comprising a frame, a conveyer for supporting the bricks, a shaft having crank disks thereon, means operated by one of said disks 105 for imparting a step-by-step movement to said conveyer, a feed slide, means operated by the other disk for actuating said feed slide, means for supplying bricks to said slide, and means for applying coating material 110 to the bricks while supported by said conveyer.

23. An improved brick veneering machine comprising a frame, a conveyer for supporting the bricks, a shaft having crank disks 115 thereon, means operated by one of said disks for imparting a step-by-step movement to said conveyer, a rock shaft actuated by the other disk, a feed slide, connections between said rock-shaft and said feed slide, means 120 for supplying bricks to said slide, and means for applying coating material to the bricks while supported by said conveyer.

24. An improved brick veneering machine comprising a frame, a conveyer for supporting the bricks, a shaft having crank disks thereon, means operated by one of said disks for imparting a step-by-step movement to said conveyer, an operating 125 rod connected with the other disks, a feed 130

- slide having a yieldable connection with said operating rod, means for supplying bricks to said slide, and means for applying coating material to the bricks while supported by said conveyer.
25. An improved brick veneering machine comprising a frame, a conveyer for supporting the bricks, a shaft having crank disks thereon, means operated by one of said disks for imparting a step-by-step movement to said conveyer, an operating rod connected with the other disks, a rock shaft having a yieldable connection with said operating rod, a feed slide actuated by said rock shaft, means for supplying bricks to said slide, and means for applying coating material to the bricks while supported by said conveyer.
26. An improved brick veneering machine comprising a frame, a traveling conveyer for supporting the bricks, means for imparting a step-by-step movement to said conveyer, a reciprocable feed slide operated in time with the movements of said conveyer, means for supplying bricks to said slide, means for applying coating material to the bricks while supported by said conveyer, and brick-discharging means operated by actuation of said feed slide.
30. 27. An improved brick veneering machine comprising a frame, a traveling conveyer for supporting the bricks, means for imparting a step-by-step movement to said conveyer, a reciprocable feed slide, means for reciprocating the same, a discharge slide actuated by the feed-slide reciprocating means, means for supplying bricks to said slide, and means for applying coating material to the bricks while supported by said conveyer.
28. An improved brick veneering machine comprising a frame, a traveling conveyer for supporting the bricks, means for imparting a step-by-step movement to said conveyer, a reciprocable feed slide, a rock shaft connected therewith, means for actuating said rock shaft, a discharging slide, a rock shaft connected therewith, connections between said rock-shafts whereby the discharge shaft is actuated by the feed shaft, means for supplying bricks to said slide, and means for applying coating material to bricks while supported by said conveyer.
29. An improved brick veneering machine comprising a frame, a conveyer for the bricks, means for actuating the conveyer, a supply chamber having a bottom opening shaped to permit the bricks to pass therethrough, a closure for said opening, and means for periodically reciprocating said closure.
30. An improved brick veneering machine comprising a frame, a conveyer for the bricks, means for actuating the conveyer, a supply chamber having a bottom opening
- shaped to permit the bricks to pass therethrough, a closure for said opening, said closure being shaped to straddle the bricks as they pass through said bottom opening, and means for periodically reciprocating said closure.
31. An improved brick veneering machine comprising a frame, a conveyer for the bricks, means for actuating the conveyer, a supply chamber having a bottom opening having its sides cut away to permit bricks carried by the conveyer to pass, a slide mounted to reciprocate through said open sides to control the discharge of material from said chamber, and means for periodically actuating said slide.
32. An improved brick veneering machine comprising a frame, a conveyer for the bricks, means for actuating the conveyer, a supply chamber having a bottom opening having its sides cut away to provide clearance for bricks carried by the conveyer, oppositely disposed closure slides working in said openings, means for periodically actuating one of said slides, and means for manually actuating the other slide.
33. An improved brick veneering machine comprising a frame, a conveyer for the bricks, means for actuating the conveyer, a supply chamber having a bottom opening having its sides cut away to permit bricks carried by the conveyer to pass, a slide mounted to reciprocate through said open sides to control the discharge of material from said chamber, means for periodically actuating said slide, and means for varying the size of the cut away portions.
34. In a brick veneering machine, a receptacle for containing veneering material and open at the bottom, endless intermittently moving means for conveying bricks beneath said receptacle, a device movable beneath said receptacle and adapted to close the opening in the bottom of the receptacle and means whereby said device closes said opening when the conveying means is in motion and opens it when said means is at rest.
35. In a brick veneering machine, a receptacle for veneering material having an opening in its bottom, intermittently moving means for conveying bricks beneath said opening, and an intermittently moving device for closing the opening, moving alternately with the conveying means.
36. In a brick veneering machine, a receptacle for veneering material having an opening in its bottom and downward extensions on opposite sides below said opening, intermittently moving means for conveying bricks between said extensions, and an intermittently moving device for closing the opening, moving alternately with the conveying means.
37. In a brick veneering machine, a receptacle for veneering material having an

- opening in its bottom and downward extensions on opposite sides below said opening, means for intermittently conveying bricks between said extensions and below said opening, and an intermittently moving device for closing the opening, moving alternately with the conveying means, and having also parts adapted to be interposed between the ends of the said brick and the extensions.
- 10 38. In a brick veneering machine, a receptacle for veneering material having an opening in its bottom, means for intermittently conveying bricks beneath said opening, an intermittently moving device for closing the opening, moving alternately with the conveying means, and means for positively pushing the veneering material through said opening.
- 15 39. In a brick veneering machine, a receptacle for veneering material having an opening in its bottom and downward extensions on opposite sides below said opening, means for intermittently conveying bricks between said extensions and beneath said opening, an intermittently moving device for closing the opening, moving alternately with the conveying means, and means for positively pushing the veneering material through said opening.
- 20 40. In a brick veneering machine, a receptacle for veneering material, an endless conveyer comprising sections jointed together, brick carrier members carried by sections of the conveyer, said conveyer traveling immediately beneath said receptacle, one of said carrier members having a section including a marginal portion thereof movable relative to the remainder, means whereby veneering material can be discharged on to a brick carried by said carriers, and means for moving said movable portion.
- 25 41. In a brick veneering machine, a receptacle for veneering material, an endless conveyer comprising sections jointed together, brick carrier members carried by sections of the conveyer, said carrier members having a section including a marginal portion thereof movable relative to the remainder, means whereby veneering material can be discharged on to a brick carried by said carriers, and means for moving said movable portion.
- 30 42. In a brick veneering machine, a receptacle for veneering material, an endless conveyer comprising sections jointed together, brick carrier members carried by sections of the conveyer, said carrier members having a section including a marginal portion thereof movable relative to the remainder, means whereby veneering material can be discharged on to a brick carried by said carriers, and means for so moving said movable portion.
- 35 In testimony whereof I affix my signature.

JOHN ELDRIDGE.
